UNITED STATES PATENT OFFICE

CHARLES SCHOFIELD, OF PHILADELPHIA, PENNSYLVANIA

CARDING PICKER

Application filed October 14, 1927. Serial No. 226,175.

This invention relates to carding machines and comprises improvements in a machine of the type shown and described in a prior United States Letters Patent Number 896,5604, dated August 18, 1908, and in which I am named as a joint inventor.

One object of my present invention is to so construct a machine for carding animal or vegetable fibers that the action of the teeth 10 of the cylinder and workers upon the fiber will have less tendency to break, tear or otherwise injure the fibers, than in carding machines heretofore employed.

Another object of the invention is to so 15 mount the workers that they may be independently adjusted relative to the carding cylinder and with respect to each other.

These objects I attain in a manner hereinafter set forth, reference being had to the 20 accompanying drawings, of which:

Fig. 1 is a side elevation of a carding machine constructed in accordance with the principles of my invention;

Fig. 2 is a longitudinal sectional elevation of a portion of the machine;

Fig. 3 is a side elevation of a portion of the machine drawn on a slightly enlarged scale for the purpose of illustrating the details of the adjusting means for the workers; and

Fig. 4 is a rear elevation of the mechanism shown in Fig. 3.

In the drawings 1 represents a casing having a concave bottom 2 inclosing the lower half of a toothed cylinder 3 carried by a 35 shaft 4, which is adapted to bearings in opposite sides of the casing 1 and is rotated in the direction of the arrow by any suitable mechanism.

Grouped together adjacent to the upper 40 portion of the cylinder 3 is a series of toothed workers 5, four of which are shown in the present instance, although a greater or less number than this may be used, as the character of the work to be performed may suggest. Each of these workers is carried by a shaft 6, adapted to suitable bearings adjustably mounted on the sides of the casing 1, and each worker is so rotated, in the direction of its respective arrow, that, while the 45 teeth of the workers, at the points where they

coact with the teeth of the cylinder, travel forwardly with the latter teeth, the movement is slower than that of the cylinder teeth, whereby the workers exercise a retarding effect upon the fibers and cause the 55 teeth of the cylinder to comb, card, or straighten out said fibers.

The workers 5 are rotated at different speeds with respect to each other and with respect to the speed of the cylinder, the first worker having the highest surface speed, the next a somewhat slower surface speed, and so on, progressively to the last worker. By reason of this construction the surface speed of the first worker may approximate that 60 of the cylinder, hence said worker will have a minimum of retarding effect upon the fibers, such retarding effect being progressively increased as the fibers are drawn forward and brought under the influence of 65 the successive workers of the series, until, by the time they have passed the last worker, the desired carding, combing, or straightening of the fibers will have been completed.

For the purpose of imparting the desired 70 differential surface speed to the workers, I have indicated means comprising a shaft 9 provided with a sprocket wheel 10 to which, and to sprocket wheels 11 on the worker 75 shafts 6, is adapted an endless chain belt 12.

The desired differential speeding of the various workers is effected by the sprocket wheels 11 being of different diameter on the successive worker shafts, the sprocket wheel 80 on the shaft of the first worker being the smallest and that on the shaft of the last worker being the largest.

The fibers which are to be subjected to the action of the machine are delivered from a feed apron 13 to a pair of feed rolls 14 and 14^a suitably rotated in the direction of the arrows, these feed rolls discharging the fibers onto the teeth of the cylinder whereby they are carried forward and subjected to the action of the various workers of the 95 series in succession, the action being a gradual and progressive one because of the differential speeding of said workers.

The fibers are delivered from the teeth of the cylinder 3 through an outlet 15 in the 100

casing 1 over an inclined apron 16 in said casing, and in order to protect the workers and yet permit ready access thereto, and also to prevent any escape of fiber at the top of the machine, the group of workers is partially inclosed within a hood 17, pivoted at 19, to the casing 1.

On one end of the main shaft 4 is the usual driving pulley 20 and on the opposite end of the said shaft is a small pulley 21 connected by a belt 22 with a pulley 23 secured to one end of a transversely extending shaft 24. Secured to the opposite end of the shaft 24 is a spur gear 25 which meshes with a spur gear 26 secured to one end of the shaft 27 which supports and rotates the lower feed roll 14. On the opposite end of the shaft 27 is a pinion 28 which meshes with a spur gear 29 secured to the shaft 9 and thereby drives the workers 5, 5. The upper feed roll 14 and apron 18 are also driven from the shaft 27 by suitable gearing.

Upon referring to Fig. 2, it will be noted that the teeth 30 of the carding cylinder 3 extend radially from the center of rotation of said cylinder, in the usual manner. The teeth 31 of the workers 5 each extend at an angle with respect to the radii of the said workers, the base portions of the teeth traveling in advance of their outer points or apexes. As above noted, the carding cylinder has a greater surface speed than that of the workers, therefore, the teeth of the workers which are pointing in a direction opposite to the direction of travel of the surface of the carding cylinder facilitates the carding action by more effectively holding or retarding the progress of the fibers through the machine, which together with the progressively increasing retardation effected by the progressively slower surface speeds of the successive workers effectively straightens the fibers into a position extending circumferentially of the carding cylinder 3 without tearing or breaking them.

Adjacent the last worker 5, I provide a stripper reel 35 comprising, in the present instance, a pair of blades 36, 36 mounted on arms 37, 37 extending radially from a shaft 38 rotatably mounted in the side frames of the carding machine. The outer transversely extending edge of each blade 36 is provided with a flexible strip 39 which engages the ends of the teeth 31 of the last worker 5, and strips any fibers which have adhered to the said teeth therefrom, laying them back on the carding cylinder 3.

On one end of the shaft 38 is a pulley 40, over which and a pulley 41 on the shaft 4 passes a driving belt 42, by means of which the stripper reel 35 is rotated.

Each worker 5 is provided with a circular flange 43 at each of its ends which prevents the fibers carried by the said workers from passing off the ends of the workers and be-

coming matted and tangled around the worker shafts, which is a common annoyance in carding machines in general use.

In order that these flanges and the teeth 31 of each worker may be properly positioned with respect to each other and with respect to the teeth 30 of the carding cylinder 3, each shaft 6 of the respective workers 5 is independently and adjustably mounted on the frame of the machine.

Each shaft 6 is rotatably mounted in a journal block 45 at each of its ends. Each journal block 45 is slidably mounted in the forked end 46 of an adjustable bracket 47, and is provided with grooves 48, 48 adapted to receive the prongs 49, 49 of the forked end 46 of the bracket 47. The bracket 47 is provided with a pair of longitudinally extending slots 50 and 51 through which are adapted to pass bolts 52 and 53 respectively. Along the longitudinal side edges of the bracket 47 and adjacent the slot 51 therein is formed integral with the bracket 47, a pair of lugs 54, 54 and at the end of the bracket 47 opposite the forked end 46 thereof is formed an integral lug 55. On the frame of the machine, adjacent the bracket lugs 54, 54 and 55, are formed frame lugs 56, 56 and 57 respectively. Passing through and in threaded engagement with each of said frame lugs 56, 56 and 57 respectively is an adjusting screw 58, 58 and 59 respectively.

The slot 50 of the bracket 47 is a snug sliding fit around the bolt 52 while the slot 51 thereof is of greater width than the diameter of the bolt 53, thereby permitting lateral as well as longitudinal movement of the bracket 47 with respect to the bolt 53, whereas the snug fit of the slot 50 permits only longitudinal movement of the bracket 47 with respect to the bolt 52.

Obviously by loosening the bolts 52 and 53 the bracket 47 and consequently the worker 5 can be adjusted radially of the cylinder 3 by setting up or backing off the screw 59. Lateral adjustment of the forked end 46 of the bracket 47, and consequently the worker 5, can be effected by manipulating the screws 58, 58 until the worker 5 is in the proper and desired position with respect to the other workers and the cylinder 3.

I claim:

1. In a carding machine, the combination of a frame, a carding cylinder rotatably mounted in said frame; a series of teeth on the surface of said cylinder; a series of rotatably mounted workers positioned adjacent the surface of said cylinder; a series of teeth on each of said workers; a shaft for supporting and rotating each worker; means for adjusting each worker with respect to the other workers and with respect to said cylinder, comprising a bracket at each end of said worker, in which said shaft is rotatably mounted and having a pair of elongated slots 130

formed in and extending longitudinally of said bracket; securing bolts passing through said slots, one of said bolts located at one end of said bracket snugly fitting its respective slot and the other of said bolts loosely fitting within its respective slot; means for moving the bracket longitudinally and with respect to said securing bolts comprising a lug on the frame at the end of the bracket opposite to that in which the worker is mounted, and an adjusting screw threaded through said lug and engaging the said end of said bracket; and means for moving the said bracket laterally at the end thereof occupied by and with respect to said loosely fitting securing bolt comprising lugs on the frame at the opposite sides of the bracket, and adjusting screws threaded through said lugs and engaging said bracket at the opposite sides thereof.

2. In a carding machine, the combination of a carding cylinder mounted for rotation in a definite direction; a series of radially disposed teeth on the surface of said cylinder; a series of rotatably mounted workers positioned adjacent the surface of said cylinder, the surface of said workers traveling in a direction consistent with direction of travel of the surface of said cylinder but at a surface speed less than the surface speed of said cylinder; teeth on said workers disposed at an angle with respect to the radii of said workers and pointing in a direction opposite to the direction of travel of the surface of said cylinder; stripping means for, and positioned adjacent to, the last worker of the series of workers, and comprising a rotatable reel consisting of a plurality of blades extending parallel to said worker, adapted to engage the said teeth thereof and to be rotated in a direction opposite to that of said worker.

CHARLES SCHOFIELD.
